Referring to the drawings, Fig. 1 shows a side view of a bowed slat cover applied to a rectangular wooden box or crate. The cover is made of a flexible material, such as wood veneer, and is applied in a bowed condition. It consists of a pair of end slats 2-2, a pair of longitudinal side slats 3-3, and a pair of intermediate slats 4-4. The end slats 2-2 are bowed upwardly, as shown, and are held in this position during the process of manufacture until they are stapled, stitched, or otherwise secured with relation to each other, thereafter the bow becomes permanent as the side slats form a chord or tie member between the extreme ends of the arc formed by the bowed slats.

- 5 In the shipment and transportation of lettuce, cauliflower, cabbage, spinach, and other commodities using a bow or bulge pack, it is common practice to employ covers and sometimes bottom sections which are bowed or sprung outwardly when applied to a crate, or similar container, so as to maintain sufficient pressure on the commodity to take up shrinkage during shipment. Covers and bottom sections employed for this purpose are usually constructed of veneer 10 strips or slats as they must be rather flexible to permit the required amount of bending, but even though material of that character is used considerable breakage is encountered as the load or stresses applied are not uniformly distributed.
- 15 The present invention is concerned with so-called unitized or manufactured slat covers; that is, covers which are assembled and completed in the factory and in this condition shipped to the individual users, the object of the invention being to provide a finished cover of the character described which can be quickly and readily applied to a crate, or like container; to provide a cover of the character described which will readily conform itself to a bow or bulge pack and which 20 will be capable of absorbing the load or stresses applied more uniformly than ordinary covers heretofore used; and further and more specifically stated, to provide a slat cover comprising a pair of cross slats and a plurality of longitudinally extending slats, one or more of said longitudinal slats being bowed and the remaining slats functioning as tie or chord members to retain the bowed slats in a bowed condition prior to and after the cover is applied to the 25 crate.
- 30
- The slat cover is shown by way of illustration in the accompanying drawing, in which—
- Fig. 1 is a perspective view of the cover.
- Fig. 2 is a longitudinal vertical section showing a crate and showing the cover applied, and
- 35
- Fig. 3 is an end view of a crate with a cover applied.

Referring to the drawing in detail, A indicates the cover section of a crate, and B the crate proper. Crates of the type disclosed are particularly intended for commodities using a bow or bulge pack, and a cover conforming to such a pack is accordingly desired.

The covering forming the subject matter of the present application is best shown in Fig. 1.

SLAT COVER

Julius J. Krohn, Arcata, Calif., assignor to California Barrel Company, Ltd., San Francisco, Calif., a corporation of California

Application April 24, 1933, Serial No. 667,556

2 Claims. (Cl. 217—56)

It consists of a pair of end slats 2-2, a pair of longitudinally extending side slats 3-3, and a pair of intermediate slats 4-4. These last-named slats are bowed upwardly, as shown, and are held in this position during the process of manufacture until the slats are stapled, stitched, or otherwise secured with relation to each other, thereafter the bow becomes permanent as the side slats form a chord or tie member between the extreme ends of the arc formed by the bowed slats.

A cover constructed, as shown in Fig. 1, will nest and can be stacked in a manner identical to ordinary slat covers. They are, however, more convenient and easier to apply to a crate as the bulged intermediate slats 4 conform more readily to the contents of the crate. When the cover, shown in Fig. 1, is applied breakage of the individual slats is not liable to happen as the intermediate slats are already bent, hence when the cover is pressed down and nailed to the end sections of the crate a uniform stress is applied; that is, the side slats 3-3 will bend to a certain extent and so will the intermediate slats 4-4 but as they have been previously bent during the process of manufacture breakage is not as liable to happen as where a cover employing straight slats is employed.

Any suitable material may be employed, whether it be wood veneer or otherwise, and any number of slats may be employed depending upon the size of the crate to which the cover is to be applied. In some instances a single bowed center slat may be sufficient, in other instances two, as shown in Fig. 1, again a wider panel-shaped bowed slat may be employed, and while this and other features are more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. A pre-bent and assembled flexible slat cover for crates comprising a pair of cross slats, one at each end of the cover, a plurality of longitudinally disposed slats forming the sides of the cover, a plurality of intermediate slats also longitudinally disposed and bowed throughout their length, said bowed slats and side slats being secured at their outer ends to the cross slats, and said bowed slats being permanently maintained in bowed condition

by the cross slats and the side slats which form a chord between the ends of the bowed slats.

2. A pre-bent and assembled flexible slat cover for crates comprising a pair of spaced straight side slats, a pair of cross slats to which the opposite ends of the straight side slats are secured and an upwardly bowed intermediate slat secured

at its ends to the cross slats and being maintained in bowed condition by the straight side slats, said cross and longitudinally extending slats being flexible and adapted to be nailed to the ends of a crate when the assembled cover is applied. 5
